(57) **CLAIM**

The ornamental design for a ground system display screen portion including graphical user interface with icon, as shown and described.

DESCRIPTION

A portion of the disclosure of this patent document contains material subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a front view of a first embodiment of a ground system display screen portion including graphical user interface with icon; and,

FIG. 2 is a front view of a second embodiment of a ground system display screen portion including graphical user interface with icon.

The outermost broken line rectangle in all figures showing a portion of the ground system display screen, and all other broken lines showing portions of the graphical user interface, are included for the purpose of illustrating portions of the article of manufacture and form no part of the claimed design.
